HANDLE FOR CAUTERY INSTRUMENTS

Walter A. Arnesen, New York, N. Y.

Application July 31, 1934, Serial No. 737,724

6 Claims. (Cl. 200—157)

This invention relates to improvements in instrument handles and more particularly to improvements in handles for cautery instruments.

Heretofore handles for cautery instruments have been made with an exposed spring contact member movable into contact with a stationary member under the force exerted usually by the thumb of the operator. Considerable pressure has been required to force the movable contact into proper engagement with the stationary member with the result that if the cautery instrument is used for any appreciable length of time by the operator, the operator undergoes considerable strain.

An object of the invention is to provide a cautery handle of such construction that the movable contact member can be actuated with a minimum of strain on the operator.

Another object of the invention is to provide an actuating member for a cautery handle so constructed as to resemble a trigger.

A further object of the invention is to provide socket members on a cautery handle of such construction that continued use of the sockets does not result in the sockets becoming permanently set due to loss of resiliency.

In achieving the objects of the present invention, a cautery handle is constructed in conventional fashion of a bar of some suitable insulating material, such as a phenol condensation product, to one end of which is secured a terminal member having mounted thereon sockets for the reception of cautery tips. This handle has secured to the top thereof a terminal member in the nature of a spring tongue forced upwardly normally by its own resiliency. Depression of this terminal member forces it into engagement with a contact in electrical engagement with one of the cautery tip sockets. In

order that this spring contact member may be forced into circuit closing position use is made of a trigger-like actuating member, in one form of the invention consisting of a lever pivoted to the side of the handle near the forward end thereof. This lever is provided with an angularly extending tongue from the top thereof adapted to engage the top of the spring contact member. The lower end of the lever is twisted at right angles and curved to fit the finger of an operator. In another form of the invention the contact member is in the nature of a lever pivoted in a vertical slot near the end of the handle and having an upstanding portion fitting in a slot in the contact member. The lower end of the lever is shaped in the same fashion as men-

tioned in the first embodiment. Movement of the lever by pressure exerted by a finger of the operator causes the upstanding part thereof to bear against the end of the slot in the contact member forcing it downwardly into circuit closing engagement.

In further achieving an object of the invention, the socket members for the cautery tips are made of some suitable metal with an attaching portion in the shape substantially of round disks from which extend, substantially tangentially, rod-like portions hollowed out for the reception of the terminals of the cautery tips. In order that these tips may be held firmly, the disk-like parts of the sockets are slotted and a part of the rod extensions are also slotted. The disk-like parts are mounted on a central shaft and are forced together by means of a screw threaded onto the shaft. In order that the sockets may not become permanently set as the result of continued compression, the disk-like parts thereof are provided with apertures through which extends a rod of insulating material. A small washer is secured around the rod in each slot in the respective sockets. This washer prevents squeezing together of part of the sockets but does not prevent such pressure application as causes locking of the cautery tips in the sockets.

Other objects, features, and advantages of the invention will become apparent from the following detailed description taken in conjunction with the accompanying drawing wherein

Fig. 1 is a side elevation of a handle embodying the invention.

Fig. 2 is an enlarged section taken substantially on the line 2—2 of Fig. 1.

Fig. 3 is a view partially in section of a modification of the invention; and

Fig. 4 is a plan view of the device shown in Fig. 3.

Referring now to the drawing and particularly to Figs. 1 and 2, 10 indicates a handle proper of the device, such handle being in the nature of a long rectangular bar of molded insulating material, preferably some phenol condensation product. This member 10 is hollowed out for the reception of conductors A. The end of one conductor is secured to a terminal and supporting member in the end of a metallic strip 11 having an enlarged round head 12. The strip 11 is held to the member 10 by means of a screw 14 which also aids in securing the end of one conductor to the strip. The head 12 is provided with a central threaded aperture for the recep-

tion of a headed bolt 15. A lock washer 16 is positioned between the head of the bolt 15 and the head 12 so that the bolt 15 can be tightened against the head sufficiently to prevent rotation of the bolt under normal operating conditions.

5 The end of the other conductor is secured within the handle to a spring contact or terminal member 17 positioned on top of the member 10 and secured to this member by means of 10 a pair of screws 18. The end of the terminal member is provided with a bent-down tongue 19, the purpose of which will be explained later. As will be seen from the drawing, the contact member 17 is bowed upwardly and due to the 15 resiliency thereof this member normally is in the position shown in heavy lines in Fig. 1.

The socket members for cautery tips comprises disk-like members 20 and 21 which have extending substantially tangentially therefrom 20 rod-like portions 22 and 23. These rod-like portions are hollowed out for the reception of the prong-like terminals 24 of the usual cautery tip. The hollowed out portions extend rearwardly 25 through the peripheries of the disks 20 and 21, such hollowed openings being indicated at 25 and 26. The disk portions 21 are slotted as indicated at 27 and 28 and the slots formed by removing part of the metal continue approximately half way the length of the rods 22 and 30 23.

30 The two sockets 20 and 21 are provided with central apertures for the reception of a sleeve 30 of some suitable insulating material, the sleeve 30 being in the nature of a tube of internal diameter to permit it to fit around the bolt 15. The 35 sockets are assembled on the sleeve 30 together with a disk of insulating material 31, and a thick washer 32 of some suitable metal. This washer 32 as shown is positioned against the side of the socket 21 and the disk 31 is positioned between the washer 32 and the socket 20. In order that the sockets may be maintained in parallelism at all times, the lower parts of the sockets, the washer and the insulating disk 31 are provided 40 with holes which can be aligned and held in alignment by means of a short rod 35 of some suitable insulating material.

45 Mounted on the rod 35 are a pair of washers 36 and 37 positioned respectively in the slots 27 and 28. These washers may be of any suitable 50 metal and are of such thickness as to substantially fill that portion of the slots in which they are located.

The sockets when assembled are mounted on 55 the bolt 15 and are held in place by means of a nut 38 which can be manually turned and which is internally threaded so that as it is rotated about the bolt it approaches or withdraws from the socket assembly. A disk 39 of insulating 60 material is interposed between the screw 38 and the socket member 2. When the parts are in the position shown in Fig. 2, rounded terminal members of cautery tips may be inserted in the openings or holes 25 and 26, and when so inserted can be locked against withdrawal and at 65 the desired angle by tightening the nut 38 against the disk 39 and consequently squeezing the socket members 20 and 21 together between the disk 39 and the head 12. The washers 36 and 37 situated in the slots 27 and 28 prevent 70 the lowermost portions of the disks 20 and 21 from being compressed materially but do not prevent the upper parts from being compressed, and consequently do not interfere with the locking 75 of the cautery tips in place. Were these

washers not present, the disks would be apt to receive a permanent set after a number of operations, since repeated contraction would eventually result in the metal of the socket members losing some of its resiliency.

5 It will be seen that one of the conductors A is in electrical connection with the socket 20 through the strip 11 and head 12. The other socket 21 however is insulated completely from the socket 20 by means of the disk 31, the sleeve 10 30, and the disk 39.

To complete the circuit for energizing a cautery tip it is necessary that the spring contact 17 be depressed until the tongue 19 engages the washer 32 which is in good electric connection with the socket 21. To facilitate depression of the contact 17 use is made of an actuating member indicated generally at 40 in the nature of a lever made of flat metal having an intermediate portion pivoted to the side of the member 10 by means of a headed bolt 41 threaded into a suitable aperture in the member 10. If desired, a spacing washer 42 may be positioned between the member 40 and the side of the member 10. This lever 40 has an upstanding flat 25 portion 44 provided with a right-angular tongue 45 overlying the contact member 17. The lower extremity of the lever 40 is twisted into a right-angular finger receiving part 46.

In the use of the handle as just described, the operator places a cautery tip with the terminals thereof in the sockets 20 and 21 and locks the tip in the desired position with the tip extending at whatever angle necessary from the axis of the handle member 10. When it is desired 35 to energize the cautery tip, the operator simply draws the portion 46 of the lever 40 from full line position of Fig. 1 to dotted line position usually by moving it from one position to another with one finger, generally his forefinger. This 40 movement of course causes movement of the tongue 45 from full line position to dotted line position (Fig. 1), depressing the spring contact 17 until the tongue 19 bears against the periphery of washer 32. In this position a complete 45 electric circuit is made through the electrode of the cautery tip. The circuit can be maintained as long as desired with a minimum of strain on the hand of the operator, since very little pressure is required through the lever or trigger to hold the contact 17 in dotted line position. In 50 actual practice it has been found that an operator may hold the contact in circuit closing position by aid of the trigger considerably longer than could be possible by pressing the contact 55 down with his thumb.

In the modification shown in Figs. 3 and 4 the end of the member 50 is provided with a vertical slot in which is pivotally mounted a central portion 55 of a lever or trigger indicated generally 60 at 56. A suitable bolt or screw 57 serves as a shaft about which the lever or trigger 56 may move. This member is made of flat metal as before and has an upstanding tongue part 58 passing through a slot 59 in the contact member 17'. The lower portion of the trigger 56 is twisted to form a finger receiving part 60 similar to member 46. As the trigger is rotated about its axis by a finger of the operator, the tongue 58 engages the forward end of the slot 59 and forces the spring contact 17' downwardly until the tongue 19' thereof makes contact with a washer 32 as in the previous modification of the invention.

75 From the foregoing it will be seen that the

present invention provides a handle for cautery instruments of such construction that an operator may use the instrument without strain for a longer period of time than possible with the instruments heretofore made. This extended length of time is made possible by the minimizing of strain upon the hand of the operator in holding the contact member in circuit closing position. Since the current necessary for energizing the cautery tip is of relatively high amperage, the contact must be relatively heavy and consequently the direct pressure necessary to depress this contact member is of a considerable value. Due to the high amperage current employed, considerable heat is generated in the contact member and consequently it has been found advantageous to have this contact member mounted exteriorly of the handle so that the heat can be dissipated as rapidly as possible. The generated heat soon becomes uncomfortable to the thumb of an operator when the contact is moved to circuit closing position by thumb pressure even though a button of insulating material is secured to the contact for engagement by the operator's thumb. However, the leverage permits a reduction in the pressure necessary to move the contact into circuit closing position when such pressure is applied to the portion 46 or the portion 60 of the trigger. The trigger contact operating member also prevents the generated heat from becoming uncomfortable to the user due to the remoteness of the finger receiver part of the trigger from the contact. The provision also of spacer washers in the slots in the socket members prevents these socket members from acquiring a permanent set, thereby greatly lengthening the life of the apparatus.

It will be understood that the invention is capable of modification over the illustrated embodiments, in view of which it is not to be limited to the arrangements shown in the drawing but is to be limited only by the scope of the following claims.

45 I claim:

1. A handle of the type described comprising a bar of insulating material, cautery tip sockets secured to one end thereof, a fixed terminal member secured to said bar in electrical connection with one socket, a spring contact terminal secured to the top of said bar and movable into electrical connection with the other socket, and a contact actuating member pivotally secured to said bar and having a portion engaging said spring contact terminal and having another portion extending below said bar and shaped to fit a finger of an operator.

2. A handle of the type described comprising a bar of insulating material, cautery tip sockets secured to one end thereof, a fixed terminal member secured to said bar in electrical connection with one socket, a leaf spring contact terminal secured to the top of said bar and flexed so that the outer end thereof extends upwardly from said bar, the outer end of said contact being provided with a down-turned tongue, said spring contact being movable into electrical connection with the other socket, and a contact actuating member pivotally secured to a side 65 of said bar, said actuating member having an upstanding portion provided with an angular tongue overlying said spring contact member, said actuating member having a depending portion shaped to fit a finger of an operator.

75 3. A handle of the type described comprising

a bar of insulating material, cautery tip sockets secured to one end thereof, a fixed terminal member secured to said bar in electrical connection with one socket, a leaf spring contact terminal secured to the top of said bar and flexed so that the outer end thereof extends upwardly from said bar, said spring contact terminal being movable into electrical connection with the other socket, and a trigger-like actuating member of flat metal pivotally secured to a side of said bar, said trigger-like actuating member having an upwardly extending portion and an angularly extending tongue overlying said spring terminal, said actuating member having a portion extending below said bar and twisted into a right-angular formation shape to fit a finger of an operator.

4. A handle of the type described comprising a bar of insulating material, cautery tip sockets secured to one end thereof, a fixed terminal member secured to said bar in electrical connection with one socket, a leaf spring contact terminal secured to the top of said bar and being provided with a slot therein near the outer end thereof, said spring terminal being flexed so that the outer end thereof extends upwardly from said bar, said spring contact terminal being movable into electrical connection with the other socket, and an actuating member comprising a trigger-like lever pivotally secured to said bar and having an upstanding portion fitting in a slot in said spring contact and having a depending portion twisted into shape to fit a finger of an operator.

5. A handle of the type described comprising a bar of insulating material, cautery tip sockets secured to one end thereof, a fixed terminal member secured to said bar in electrical connection with one socket, a leaf spring contact terminal secured to the top of said bar and being provided with a slot therein near the outer end thereof, said leaf spring contact terminal being flexed so that the outer end thereof extends upwardly from said bar, said contact member being movable into electrical connection with the other socket, and an actuating member for moving said contact member comprising a trigger-like lever pivoted in a slot near the end of said bar, said lever having an upstanding portion fitting in the slot in said contact member and having a depending portion twisted into shape to fit a finger of an operator.

6. A handle of the type described comprising a bar of insulating material, a socket supporting member secured to the end of said bar, cautery tip sockets mounted on said supporting member, each socket being composed of a disk-like member having a hollow rod extending substantially tangentially therefrom, said disk-like member being slotted and said hollow bar being partially slotted, a washer positioned in the slot of each disk-like member substantially opposite to said hollow bars, means carried on said supporting member for applying pressure to said sockets, a terminal member on said handle in electrical connection with one of said sockets, a spring contact member secured to the top of said bar and movable into electrical connection with the other of said sockets, and a trigger-like lever pivotally secured to said bar and having a portion engaging said spring contact member for moving it into electrical connection with the second socket.
